UNITED STATES PATENT OFFICE.

GEORG KIRKEGAARD, OF NEW YORK, N. Y., ASSIGNOR TO IMPERIAL STOPPER COMPANY, A CORPORATION OF MAINE.

CAPPING-MACHINE.

No. 922,777.

Specification of Letters Patent. Patented May 25, 1909.

Application filed May 6, 1908. Serial No. 431,148.

To all whom it may concern:

Be it known that I, GEORG KIRKEGAARD, a citizen of the United States, residing at the city of New York, in the borough of Brooklyn and State of New York, have invented certain new and useful Improvements in Capping-Machines, of which the following is a full, clear, and exact description.

This invention relates to machines for applying caps or stoppers to bottles.

The particular kind of stopper which the machine is adapted to operate upon comprises a metal cap having a packing disk inside thereof and having a depending flange which is adapted to be forced into locking engagement with an annular shoulder on the exterior of the bottle to hold the cap thereon with the packing disk under compression against the mouth of the bottle. Owing to the crudity with which bottles are manufactured, it is found that they often vary in size, some being of less diameter at the mouth than the normal, while others are of greater diameter. It is also found that the bottles vary in length considerably, and it is this latter variation that my present invention has to deal with. In capping machines, it is customary to place the bottle upon a table or shelf where it rests while the cap is being applied by means of a plunger which is forced downward for a certain length of stroke. If the bottle is longer than usual, an extraordinary pressure will be exerted upon it, unless some means of compensating for the extra pressure is provided.

The object of my invention is to do this and it consists in supporting the table or shelf upon a vertical screw, which passes through a nut which is free to rotate in case the screw is forced through it with sufficient power, while the screw is prevented from rotating. Thus, by arranging the pitch of the screw so that the amount of friction required to be overcome between the screw and the nut before the latter will turn, will balance the downward force which is applied by the machine to a bottle of normal length, the table will be unyielding, unless a bottle of abnormal length is encountered, when the pressure upon the table will overcome the friction between the screw and the nut, and the latter will rotate and permit the table to retreat, thus preventing breakage of the bottle.

My invention also includes means for au-

tomatically returning the table to its normal level after the bottle has been removed.

In the accompanying drawing, Figure 1 is a side elevation of a capping machine provided with my improvements; and Fig. 2 is a vertical central section of that portion of the machine including the bottle table and its support.

Referring to the drawings by reference numerals, 1 indicates a standard or frame of the machine; 2 the capping head or die which is caused to reciprocate through strokes of definite length by application of power through the pulley 3.

4 is a table or shelf upon which the bottle is placed to be acted upon by the machine. This table is supported upon a vertical spindle 5, provided with a screw thread 6. The spindle is arranged vertically in suitable passages formed in two brackets 7 and 8 carried by the main frame of the machine, the spindle having a spline 9, or equivalent means permitting of its vertical movement, but preventing rotary movement. Confined between the two brackets 7 and 8 is a nut 10 through which passes the threaded spindle, the threads of the spindle engaging those in the nut. The nut is mounted upon ball bearings 11, so as to turn with the least possible friction, except that which is especially provided for; it cannot move longitudinally with the spindle. The nut is also formed with a cylindrical exterior surface bounded by flanges 12 forming a drum around which a cord 13 is wound. This cord leads from the drum 90 or nut over the guide pulley 14, and then is attached to and holds in suspension, a weight 15, which moves vertically in the hollow frame of the machine. A downward movement of the spindle 5 tends to rotate the nut 95 in a direction to wind up the cord and raise the weight, and the downward movement of the weight tends to rotate the nut in a direction to raise the spindle.

The operation is as follows: The pitch of the screw 6 is predetermined in proportion to the downward thrust which is exerted against the table by the capping head when applying a stopper to the bottle; the steeper the screw, the less will be the friction between the screw and the nut. When pressure is applied downward upon the screw, the nut will be caused to rotate only when this friction is overcome. Accordingly, a pitch is selected which will prevent rotation of the 110

nut by any downward pressure less than that applied when a bottle of normal length is acted upon, but which will cause the nut to rotate when that normal pressure is exceeded. Thus, when a bottle of abnormal length is acted upon, the extraordinary pressure upon it will be compensated for by the retreat downward of the table, the nut thereby being caused to rotate and allowing the screw to move downward without turning. As soon as the bottle has been capped and removed from the machine, the weight rotates the nut in the opposite direction, comparatively little power being required to do this, and the table is lifted to its normal level which is determined by a limiting collar fixed upon the lower end of the screw and striking the bracket 8.

What I claim, is:

20 1. In a bottle capping machine, a table upon which the bottle rests while being capped, a screw threaded spindle supporting said table and adapted to move longitudinally but not rotarily, and a nut through 25 which said spindle works and which is free to rotate, said spindle having a steep thread adapted to cause the rotation of the nut when the table is depressed, substantially as described.

2. In a bottle capping machine, a table 30 upon which the bottle rests while being capped, a screw threaded spindle supporting said table and having a longitudinal but not a rotary movement, a nut in which the spindle works and which is prevented from partaking of the longitudinal movement of the spindle, said spindle and nut having a steep thread whereby the nut is rotated by an abnormal tendency of the spindle to move through it.

3. In a bottle capping machine, a table upon which the bottle rests while being acted upon, a screw threaded spindle supporting said table and having a longitudinal but not a rotary movement, a nut through which 45 said spindle works and which has a rotary movement but no longitudinal movement with the spindle, and a cord wound around said nut suspending a weight, and a stop for limiting the longitudinal movement of the 50 spindle in one direction.

In testimony whereof, I subscribe my signature, in the presence of two witnesses.

GEORG KIRKEGAARD.
